PHOTOGRAPHIC LIGHTING SYSTEM

Samuel Hershberg, Brooklyn, N. Y.

Original application September 15, 1934, Serial No. 744,225. Divided and this application September 21, 1934, Serial No. 744,888. Renewed March 14, 1939

15 Claims. (CL 240—1.3)

This invention relates to a photographic lighting system forming a unit in the system of photography embodied and described in your applicant's application for patent, filed in the United States Patent Office on September 15, 1934, and bearing Serial Number 744,225, of which this application is a division.

This invention relates generally to a system of photographic lighting and more particularly to such a system in which the operation of the various lighting sources and their positioning is accomplished in a substantially automatic manner.

The main object of this invention is the provision of a system of photographic illumination whereby an unskilled operator is enabled to produce a photograph of a quality comparable to that produced by a finished and experienced artisan, and whereby a skilled and experienced artisan is enabled to produce more photographs in a given amount of time and of a better quality than heretofore, owing to a substantial reduction in manual manipulation of the illuminating sources.

Another object of this invention is the reduction in operating costs of the various sources of illumination owing to: a saving in space by virtue of the compact and cooperative arrangement of the various illuminating sources; saving of power costs since bright illumination is used only during actual exposure time; saving of sensitized material costs because high speed papers may be used instead of film since this lighting system possesses high actinic efficiency; saving of labor in the substitution of automatic operations for previously existing manual ones; and finally a saving in general costs owing to the production of a higher average of perfect prints.

A further feature of this system of photographic illumination resides in the elimination of guess-work in the positioning of the sources of illumination and the substitution therefor of a predetermined scientific technique.

A still further feature of this invention is the provision of a process whereby a change in the lighting of the subject to conform with a change in position of the subject is readily accomplished. This process involves the mere aiming of one mirror directed to the sitter which act of aiming automatically shifts the light so that it falls upon the subject in the proper direction and intensity.

The aforementioned objects and features of the system of lighting together with other incidental techniques and processes will hereinafter

more fully appear in the progress of this disclosure and as pointed out in the appended claims.

In the drawings: Figure 1 is a left side view in elevation of the lighting system, it being understood that all directions set forth in this specification refer to the right and left hand of the operator as he faces the subject from his position at the controls of the lighting system, while when the subject's face is described left and right side mean the subject's right and left hand.

Figure 2 is a plan view of the lighting system.

Figure 3 is an elevational view of Figure 1 along the line 3—3 thereof.

Figure 4 is an enlarged and partial medial transverse section along the line 4—4 of Figure 2.

Figure 5 is a plan view of the illuminating sources of Figure 3 along the line 5—5, thereof.

Figure 6 is a front view in elevation of the mechanism for tilting the overhead spotlights, the outer casing of said mechanism being partly broken away.

Figure 7 is an elevational view of Figure 6 along the line 7—7 thereof.

Figure 8 is an enlarged view in plan showing a portion of the control means for changing the direction of the lighting relative to the subject as indicated along line 8—8 of Figure 1.

Figure 9 is a wiring diagram showing schematically the electrical circuits used in the practice of this system of photographic lighting.

The lighting system is supported by a vertical framework comprising three upright members 800 projecting upwardly from any suitable base or the forward end of a camera stand 22 as indicated on Figure 1 of the accompanying drawings. These upright members 800 are joined at the upper terminals thereof, by a horizontal connecting bar 801, the said connecting bar serving as a support for a depending upright member 800', a cross section of the said four upright members forming the corners of a substantial square. Panels 828 attached to the upright members 800 and 800' from the connecting bar 801 to point above the base or camera stand form an enclosure for the control-mechanism of the lighting system.

Extending from the connecting bar 801 are two parallel and horizontal frame members 802 adapted to support the main lighting dome and related mechanism as will be more fully described below. The frame members 802 are reinforced by two braces 803 extending from the frame members 802 to the forward upright members 800. Horizontal frame members 802 are

fixed in position by transverse spacers 806" at the forward ends thereof and 806' at the rear ends. Behind spacer 806" is another transverse spacer 804 having mounted thereon by studs 805' a parallel reinforcing member 805 while a short distance forward of spacer 806' is another similar and parallel spacer 806. Parallel and below spacer 804 is another cross member 807 depending therefrom by means of studs 807'. Rotatably suspended below cross member 807 by means of a bolt and nut 808 is a plate 809 through aligned central orifices in member 807 and plate 809. At the outer ends of plate 809 are affixed the upper circular surface 814 of the lighting dome 811 and two spaced parallel bars 810, the said bars 810 being disposed at a ninety degree angle with the plate 809. The bars 810 are shown at right angles to reinforcing member 805 on Figure 2 of the accompanying drawings, while plate 809 lies parallel to and below member 805 as seen in Figure 4. Plate 809 is rotatably actuated by means of a longitudinal tie bar 816 pivotally connected to one end of said plate, the said tie bar 816 being controlled by a handle 826 situated on a small panel 829, the latter superposing the panel 828 which faces the operator.

The rotary motion of handle 826 is communicated to the rod 816 in the form of longitudinal reciprocal motion, through the following structure: Handle 826 is mounted upon the outer end of a short shaft 825 which is journaled between panels 829 and 828. Shaft 825 does not extend inwardly beyond panel 828 and has mounted intermediate the length thereof a sprocket 823 shown on Figure 1. A chain 822 engaging sprocket 823 travels upwardly over an idler sprocket 821' rotatably mounted on the end of a short stud projecting outwardly and perpendicularly of panel 828, see Figure 3. Numeral 824 represents a spacer which supports one end of panel 829 off of panel 828, said spacer being disposed below the supporting stud for sprocket 821'. Chain 822 continues upwardly to engage a sprocket 821 mounted on the outer terminal of a shaft 820 while the other end of said shaft carries a worm 819. Shaft 820 is journaled just inwardly of sprocket 821 in panel 828 while the supporting means for said shaft adjacent worm 819 is not shown. Worm 819 engages a gear 818 mounted on a short stud depending from spacer 806'. Gear 818 has a radial arm 817 affixed thereto adapted to swing in a horizontal plane and thereby cause the rod 816 which is pivotally connected to the outer end of said arm, to longitudinally reciprocate. Handle 826 is provided with a known position indicator 827.

Lighting dome 811 is provided with a circular upper surface 814, a depending cylindrical surface 813 from the perimeter thereof, a frustum 60 of a cone surface 812 extending outwardly from the lower edge of 813 and a depending cylindrical surface 811' from the lower perimeter of 812. Lowermost cylindrical surface 811' is provided with diametrically opposed openings 811'' and a circular base plate 815 affixed to and extending beyond the lower edge of the cylindrical surface 811'.

Affixed to the under surface of 814 are a series of sockets concentrically arranged to carry bulbs 70 855.

Affixed to the ends of bars 810 are two spaced and parallel bars 832 and 833 being at right angles to bars 810. At each juncture of these bars, there being four altogether, vertically depending rods 834, 835, 836 and 837 fix the inter-

section of the cross bars thereat, and at the lower end of each rod there is provided an orifice. Rods 834 and 835 are connected immediately above the lower extremities thereof by a horizontal spacer 838 (seen in Figure 3 in dotted lines) through which the said rods penetrate, while 840 represents a horizontal frame member contacting spacer 838 at the lower surface thereof and is penetrated and supported by said rods 834 and 835. Rods 836 and 837 similarly carry corresponding spacer 839 and frame member 841. Numerals 840' and 841' represent guy wires connecting the extremities of frame members 840 and 841 to the bars 810 and serve to support the said frame members. Frame members 840 and 841 are provided at the extremities thereof with depending vertical guide-ways 842, 843, 844 and 845. Guide-ways 842 and 843 together and guide-ways 844 and 845 form race-ways for plates 846 and 846' respectively. Plates 846, 846' carry illuminator housings 851 and 852 respectively, adjacent the upper edges thereof, the said housings corresponding in structure and being oppositely disposed. Figure 5 of the drawings shows housing 851 in detail and thus also brings out the details of housing 852. Housing 851 is supported by affixation to the inner surface of plate 846 and constitutes a box-like structure having a removable inner translucent wall 853 to permit the penetration of light therethrough from incandescent bulbs or light sources 854, 855 and 856 mounted within said housing. Translucent wall 853 may be composed of any suitable substance known in the art such as "opal" glass, or tracing cloth. Projecting rearwardly from and affixed to plate 846 adjacent the lower edge thereof, is a bar 860 carrying at its outer extremities a housing 862 having therein an incandescent bulb 862' and having an inner wall comprising an outer sheet of clear glass 864 and an inner sheet of transparent material 865 having an image thereon. Sheet of glass 864 has the inner surface thereof lightly silvered so that when bulb 862' is not illuminated, sheet of glass 864 acts as a mirror while when bulb 862' is illuminated, the image on transparent material 865 is made visible through sheet of glass 864.

Projecting forwardly and downwardly from and affixed to the inner surface of plate 846 is a bar 847 carrying at the outer end thereof a housing 848 having a bulb 849 therein. Housing 848 is positioned below the level of housing 862 as best seen in Figure 3 of the drawings.

Housing 852 together with the appurtenant structure, being the counterpart of housing 851 55 and its appurtenant structure as above described, is incompletely shown in Figure 2 whereon 846' represents a movable plate, 857, 858 and 859 represent incandescent bulbs, 849 represents a bar carrying a housing 850, 861 represents a bar carrying a housing 833. Plates 846 and 846' are vertically and slidably displaceable and thereby serve to vertically position the housings 851, 852, 60 862, 863, 848 and 850.

Plate 846 has affixed to the upper edge thereof two cables 866' and 869', the said cables being substantially parallel and flexible. Cables 866' and 869' rise vertically turning inwardly about a pair of idler pulleys being positioned at the junctions of frame member 840 and guide-way 842 and frame member 841 and guide-way 843. The said cables continue from the idler pulleys to drums 866 and 869 respectively where they are affixed. Drums 866 and 869 are keyed to a horizontal shaft 870, the said shaft being jour- 75

nalled at the ends thereof in brackets 833' and 832'.

Similarly, plate 846' is provided with cables 867' and 868' turning about a pair of idler pulleys positioned at the junctions of frame member 840 and guideway 844 and frame member 841 and guideway 845. The said cables continue from the idler pulleys to drums 867 and 868 respectively where they are affixed. Drums 867 and 868 are keyed to a horizontal shaft 871 journalled at the ends thereof in brackets 833'' and 832''. Brackets 833' and 833'' depend from the forward edge and ends of bar 833 while brackets 832' and 832'' depend from the rear edge and ends of bar 832.

Shafts 870 and 871 carry sprockets 872 and 873 respectively immediately forward of drums 869 and 868, said sprockets being interconnected by a chain 874. Shaft 871 at the forward end thereof which projects forwardly of bracket 833'', carries sprocket 875. The said sprocket 875 is connected by means of a chain 876 to a sprocket 877 which latter is affixed to the forward end of a short shaft 878. Shaft 878 is journalled at its forward end by penetrating a plurality of plates 879, 880 and 881 as best seen in Figure 7, and at its rear end in a bracket 804', the latter depending from the rear edge of reinforcing member 804. The rear end of shaft 878 projects beyond its journal and connects with a universal joint 882, the latter being affixed to the forward end of a shaft 883. Shaft 883 is in turn journalled at its rear end in a bracket 885 and connects with a shaft 888 by means of a pair of bevel gears 884 and 887 as best seen on Figure 8. Bracket 885 is supported by a short cross bar 886, the latter being supported by the parallel spacers 806 and 806'. Shaft 888 carries thereon a sprocket 889 which is connected by a chain 890 to a sprocket 891, the latter being carried on shaft 892. Shaft 892 is journalled by means of orifices in upright members 800, the said upright members being the two forward ones. It is seen from the foregoing mechanism that motion from shaft 892 is communicated to shafts 870 and 871 resulting in the raising and lowering of plates 846 and 846'.

Shaft 892 is provided with a concentric drum 893 which has coiled thereabout a flexible cable 894. One end of cable 894 is affixed to the housing 933 while the other end of said cable is coiled about another drum 895 from which drum the said cable continues and terminates in affixation to any suitable mechanical means for controlling the length of said cable 894 such as a drum and handle positioned on the control panel. The disposition of cable 894 is best seen in Figure 1 wherein said cable rises from housing 933, frictionally engages drum 893, proceeds downwardly to frictionally engage drum 895 and then offsets therefrom to run toward the control panel. Drum 895 is concentric with shaft 896, the said shaft 896 being journalled by means of orifices in the two forward upright members 800 but at a point below the mounting of shaft 892.

The housing 933 aforementioned is divided into two illuminating chambers by a vertical intermediate wall 934, the said housing having mounted therein incandescent bulbs 935, 936, 937 and 938, two in each chamber as seen in Figure 8. Motion of the cable 894 is directly communicated to the said housing 933, the motion of said cable also serving to raise and lower housings 851 and 852. Housings 933, 851 and 852, 862 and

863, and 848 and 850 move in unison while the vertical positioning of the said housings is a function of the relative length of cable 894.

Situated within the lighting dome 811 are two known spot lights 897, 898, being provided with lenses 899 and 900, condensing mirrors 901 and 902, incandescent bulbs 903 and 904 and sockets for said bulbs 905 and 906, respectively. The size of the diverging beam emitted by said spot lights is controlled by the shifting of the sockets within said spot lights by any known means such as linear slots 911 and 912 wherein sockets 905 and 906 are adjustably mounted by means of depending bolts 907 and 908 from the said sockets and nuts therefor 909 and 910. Spot light 897 is trunnioned between the lower ends of vertical rods 835 and 837 by means of trunnions 897' while spot light 898 is trunnioned between the lower ends of vertical rods 834 and 836 by means of trunnions 898'. The spot lights, being thus pivotally mounted, are capable of being tilted in a vertical plane thereby casting the beams of light emitted from the said spot lights 897 and 898 upon two screens 943 and 944 respectively, said screens being more fully described below. Projecting forwardly in the plane of the horizontal from the side walls adjacent the rear edge of each of the spot lights 897 and 898 are fingers 913 and 914 respectively. Fingers 913 and 914 are pivotally connected by means of links 915 and 916, the latter being joined at the upper ends thereof, to a link 917. Link 917 is caused to move either up or down by reason of communication of motion from shaft 878 thereto through pinion 932 carried by shaft 878, gear 930 carried by shaft 931, the latter shaft also carrying pinion 929, gear 928 carried by shaft 927 which latter carries plate cam 922, follower 921 mounted on the outer end of lever 920, the latter being connected by means of shaft 919 to lever 918 in bell crank fashion, the said lever 918 being pivotally connected to the upper end of link 917. The above described assembly is best shown in Figures 6 and 7 in which plates 879, 880 and 881 constitute the mounting for the assembly and are maintained in parallelism by virtue of connecting spacers 923, 924, 925 and 926. Shaft 931 is suitably journalled between plates 880 and 881. Shaft 927 is suitably journalled in plates 879, 880 and 881 while shaft 919 rotates within a sleeve 879', the said sleeve being affixed and extending through plate 879.

By reason of the fact that the spot lights 897 and 898 derive their motion from shaft 878 which latter in turn derives its motion from shaft 892 which said shaft 892 derives its motion from the movement of cable 894 and by reason of the fact that housings 851, 852, 862, 863, 848, 850 and 933 derive their motion also from the movement of cable 894, it is therefore seen that movement of all the sources of illumination, except bulbs 955, vertically, with relation to the sitter, is synchronized and coordinated.

Screens 943 and 944 heretofore mentioned are composed of any suitable flexible material such as 65 cotton or linen and have provided on the inner surfaces thereof a coating of suitable light reflecting and diffusing material such as aluminum paint or dull white paint. Screens 943 and 944 are supported at the upper ends thereof by affixation to and winding about spring rollers 941 and 942, the said screens extending downwardly over direction controlling idlers 945 and 946, 949 and 950 and finally terminating in weighted edges 953 and 954 respectively, all as best seen 75

in Figure 3. Spring rollers 941 and 942 are provided with the usual ratcheting means of ordinary window-shade rollers. In order to raise or lower screens 943 and 944, edges 953 and 954 thereof are manipulated like ordinary window shade rollers. Rollers 941 and 942 are disposed parallel to bars 810 and are mounted upon brackets 939 and 940 respectively, said brackets projecting upwardly from the outer ends of bars 832 and 833. Idlers 945 and 946 are mounted between the upper ends of upright arms 947, 947' and 948, 948', said arms projecting upwardly from frame members 840 and 841 while idlers 949 and 950 are mounted between the outer ends of lateral arms 951, 951' and 952, 952' respectively, said arms projecting laterally and outwardly from guide-ways 842, 843, 844 and 845, respectively.

For the connecting and disconnecting of electrical current to the various sources of illumination described hereinabove, a known segmental rotary switch 830 is provided. The said switch 830 is mounted upon an auxiliary panel therefor 830' located on panel 828 directly forward of auxiliary panel 829. Switch 830 is operated by means of an operating lever 957 which projects radially from a short shaft 958, the said shaft being journaled in panels 850', 961 and 962, the said panels being in parallel and spaced relation. Panel 961 is composed of any suitable non-conducting material and is supported by plate 962 by means of connecting spacers 963. Shaft 958 is provided with another radial arm 959 which is similar and parallel to operating lever 957 but 35 which is affixed to shaft 958 at a point between panel 830' and panel 961. Arm 959 carries on the inner surface thereof a series of contact brushes 960 which are adapted to successively make and break contact with radially disposed 40 and concentric conducting segments *a*, *b*, *c*, *d*, *e*, *f*, *g*, *h*, *j*, *k* and *m*, the disposition of said segments being best shown in Fig. 9. Numeral 956 represents an insulating post projecting outwardly from the upper end of operating lever 45 957 and serves to carry the operating handle for switch 830.

Switch 830 in its upper vertical position closes no circuits while by virtue of the staggered arrangement of the segments thereabout, the said 50 switch is capable of seven distinct positions when rotated either left or right of the aforesaid upper vertical position.

Situated directly below and on the same plane with auxiliary panel 830' is another auxiliary panel 831 carrying thereon three known toggle type switches 964, 965 and 966. Switches 964 and 966 each either make or break a single circuit while switch 965 either makes or breaks two circuits simultaneously.

60 In the operation of the lighting unit, the subject is seated or allowed to stand along the vertical axis of lighting dome 811. At this point in time the operator decides whether a left or right profile of the sitter is desired, or as in the case of 65 the average sitting where a series of different views will be made, either the right or the left profile may be taken first. Assuming that the right profile is to be photographed first, switch 964 is shifted to its on position thereby completing a circuit from the electrical line through conductors 967 and 968 to the outlet *n*. Current travels from outlet *n* by means of conductors not shown in the drawings to bulbs 904, 936 and 857. The 70 illumination of bulbs 904, 936 and 857 lights up 75

the features of the sitter sufficiently for the proper focussing and composition.

It is understood that the rotation of the lighting dome 811, together with horizontal frame members 840 and 841 and all the mechanism depending therefrom and the manipulation of the control associated with cable 894 may be effected now or at any time subsequent to the camera focussing of the sitter, the said rotation being accomplished by manipulating handle 826. Handle 826 and the control for cable 894 are rotated until the sitter is able to see his reflection in the mirrored surface in the housing 863, it being understood that all of the above steps are taken for the photographing of the right profile and all the steps hereinbelow until the contrary is stated are for the photographing of the right profile of the sitter. The extent of rotation of dome 811 and the control for cable 894 are controlled by the sitter's seeing his full view in the mirrored surface of housing 863 when looking forward, and in order that the sitter see such full view, the latter gives the operator instructions as to the extent to which the said dome 811 must be moved by means of handle 826 and 20 the extent of rotation of the control for cable 894. The rotation and final position of dome 811 and the final position of the control for cable 894, by reason of the fact that the relative spatial interrelation of the various illuminating sources 30 rotatable therewith has been predetermined relative to housing 863, results in proper illumination of the subject in all planes. The relative spatial interrelation of the various illuminating sources follow the pattern of the approved style for a 35 particular position of the sitter and it is from this pattern that your applicant makes automatic such illumination for different positions of the sitter in the several upright positions and in the several face positions.

40 Rotary switch 830 is moved in a clock-wise direction to its first consecutive "on" position, that is, when one of the brushes 960 contacts the conducting segment *a*, said movement resulting in completion of a circuit to outlet *p* through conductor 967, resistor 969', conductors 970, 971 and 968, and also switch 965. Current travels from outlet *p* by means of conductors not shown in the drawings to bulb 848'.

The rotation of dome 811 and the rotatable elements therewith results in positioning housing 863 so that the head of the sitter is situated between said housing and the lens of the camera. The effect therefore of the illumination of bulb 848' is to outline the head of the subject in so 55 called "back-lighting" or in "Rembrandt" style. If these last mentioned effects are not desired, toggle switch 965 is shifted to its "off" position thereby opening the circuit to bulb 848'.

Switch 830 is now advanced in a clock-wise 60 direction to its second position thereby contacting conducting segment *c* completing a circuit therethrough to outlet *u*. Current travels from outlet *u* through conductors not shown in the drawings to bulb 863' which upon illumination 65 makes the mirrored surface in housing 863 transparent so that the sitter is able to see the image therebehind in said housing. The purpose of illuminating housing 863 at this time is to further attract the attention of the sitter to this point 70 so that his head and eyes may appear properly directed in a finished photograph; furthermore, the subject matter of the image is conveniently alterable by merely substituting different transparencies therein. This device, utilizing known 75

principles of psychological suggestion aids in the inducement of pleasant expression on the sitter's countenance.

Switch 830 is now advanced in clock-wise direction to its third position thereby contacting conducting segment *e* completing a circuit therethrough to outlet *v*. Current travels from outlet *v* through conductors not shown in the drawings to bulbs 955. Illumination from bulbs 955 is reflected from the upper surface of plate 815 through the openings 811' and is in turn reflected from screens 943 and 944 upon the sitter. Because of the multiplicity of bulbs 955 and the indirectness with which the light therefrom reaches the sitter, said light is highly diffused and of sufficiently low intensity so that it constitutes "general" or so called "atmosphere" illumination.

Switch 830 is now advanced in clock-wise direction to its fourth position thereby contacting conducting segment *f* completing a circuit therethrough to outlet *w*. Current travels from outlet *w* through conductors not shown in the drawings to bulb 935 serving thereby to increase or augment the quantity of illumination being cast by bulb 936 from one of the chambers of the housing 933.

Switch 830 is now advanced in clock-wise direction to its fifth position thereby contacting conducting segment *h* and completing a circuit therethrough to outlet *x* whence current travels through conductors not shown in the drawings to bulbs 858 and 859, serving thereby to augment the illumination already being cast by housing 852.

Further clock-wise advancement of switch 830 to its sixth position results in contacting conducting segment *K* thereby completing a circuit through conductors 967 and 969 which short circuits the circuit comprised of resistor 969' and conductor 970. The shortcircuiting of resistor 969' causes all of the light sources which have been receiving current therethrough to increase to their maximum brilliancy so that the combined actinic power of said sources of illumination is of the proper degree with relation to the shutter timing of the camera in the camera unit. It is to be noted at this point that the reason for illuminating the various light sources in successive steps of greater brilliancy rather than to bring them on simultaneously is to avoid excitement, fright, starting and squinting of the sitter.

Since all of the illuminating sources have been energized as has above been set forth, the exposure may be caused to take place by advancing switch 830 in a clock-wise direction to its final and seventh position thereby contacting conducting segment *m* which closes the circuit to solenoid 475 which may be arranged to actuate the shutter of the camera. If the operator desires to leave his position adjacent the switch 830 to take a position from which he may better view the facial expression of the sitter, he may leave switch 830 in its sixth position and release the camera shutter by closing switch 971 indicated schematically on Figure 9 of the drawings. Switch 971 is a conventional switch of a type adapted to remain normally in an open circuited position, but which closes while under manual pressure. Said switch 971 is connected to one end of a two-conductor cable of substantial length, and is not shown in the drawings other than as above indicated.

After exposure has been completed, switch 830 is cranked anti-clockwise to its upper vertical

position, which extinguishes all of the lights except those receiving current through toggle switch 964.

Where it is desired to photograph the left profile of the sitter, all of the above mentioned operations are repeated, except that they are performed in the opposite direction. Thus toggle switch 964 is shifted to its "off" position, which extinguishes bulbs 904, 936 and 857. Next, toggle switch 966 is moved to its "on" position thereby completing a circuit to outlet *o*, whence current travels via conductors not shown, to bulbs 903, 937, and 854. Next, the camera is properly positioned along its track, and focussed, in a manner identical with that when the right profile was photographed.

Rotary switch 830 is now moved anti-clockwise to its first consecutive on position, thereby contacting segment *b* and completing a circuit therethrough to outlet *q*, whence current travels via conductors not shown, to bulb 850'. If "back lighting" is not desired, switch 965 is shifted to its "off" position. Handle 826 is now rotated until the sitter is able to see his full head-on image in the mirrored surface of housing 862.

Switch 830 is now rotated anti-clockwise to its second position thereby contacting segment *d* completing a circuit to outlet *t* and therethrough via conductors not shown to bulb 862'.

Next, switch 830 is moved to its third anti-clockwise position thereby contacting segment *e*, thus illuminating bulbs 955 as set forth above, since segment *e* is continuous in both clockwise and anti-clockwise revolutions of an arm 959. Switch 830 is then shifted anti-clockwise to its fourth position thereby contacting segment *g* completing a circuit therethrough to outlet *s* and thence via conductors not shown to bulb 938. Next, switch 830 is moved anti-clockwise to its fifth position, thereby contacting segment *j* completing a circuit therethrough to outlet *r* whence current travels via conductors not shown to bulbs 855 and 856.

When switch 830 is further rotated in an anti-clockwise direction to its sixth and seventh positions, the circuits completed thereby are identical to those which were completed in the sixth and seventh positions in the clockwise rotation thereof since segments *k* and *m* are continuous in both vertical halves of the plate 961.

While as stated hereinabove, the sitter is placed to expose either his right or left profile to the lens of the camera, it is to be understood that any intermediate angle may be made by the sitter's head, from full face to absolute profile, and since with the shifting of the sitter's head the corresponding housing 863 or 862 will have to be rotated so that the sitter may see his full face reflected therefrom, it follows that all of the related light sources will be correctly positioned in the horizontal plane.

The intensity of light emitted by housings 851 and 852 is greater than that emitted by housing 933, so that the former 851 and 852 constitute the "drawing" or "accentuating" light sources while the latter 933 constitutes the light source which serves to heighten the tones of the shadow portions of the photograph. Where the sitter sees his reflection in housing 863 and switch 830 is rotated clock-wise or sees his face reflected in housing 862 and switch 830 is rotated anti-clockwise, an approved style of lighting results in which the greater portion of the face seen in the photograph is less brilliantly illuminated than the lesser portion of the face. Where the sitter

sees his reflection in housing 862, yet the sitter shows his right side or the right side of his face to the lens and switch 830 is rotated anticlockwise, or conversely, where the sitter turns his head to his right thus showing the left side of his face to the lens, and sees his image reflected from housing 863, and switch 830 is rotated in a clockwise direction, another approved style of lighting results, which is so called "open" lighting. 10 In "open" lighting the greater portion of the face is more intensely illuminated and the lesser portion of the face is less brilliantly illuminated.

Since most of the light which falls on the face of the sitter falls at an angle of approximately 15 forty-five degrees, because of the automatically proper coordination between the position of housings 863 and 862, and the vertical positioning of the movable light sources, as has been set forth above, this system is capable of many other 20 approved styles of lighting which will always be basically correct. In the hands of a skilled operator, the versatility of the lighting system is readily seen. By studying the image of the sitter in the groundglass handle 826 may be turned at random 25 until a pleasing effect is produced, and since the rotation of switch 830, for the most part, serves to increase the intensity of the light sources, rather than inaugurate new ones, composition decided upon at low intensity will retain its quality 30 when the illumination is sufficiently intense for exposure.

In the hands of an unskilled operator, this lighting system may be operated so that very little 35 judgment is required. For normal lighting effects, vertical and horizontal positioning of the light sources is semi-automatic. The proper housing 862 or 863 is aimed by merely turning handle 826 and the control for cable 894 until the sitter can see both of his ears therein. Where it 40 is desired to have an unskilled operator duplicate unusual effects, these may be originally determined by a skilled operator, and all the unskilled operator need do is follow explicit instructions involving very little judgment. Dial 827 being 45 accurately calibrated, he need only manipulate handle 826 until the pointer coincides with a certain calibration marking on the dial. The control for cable 894 may have a similar calibrated dial. In this manner, a good lighting style once 50 conceived may be reexecuted at will.

Where the subject is possessed of unusually fair complexion or light hair, proper lighting may be simply obtained by shifting switches 964 or 966 to their "off" position. In that case, composition 55 and focussing is performed before this is done or focussing is performed with switch 380 advanced in either direction the requisite number of steps.

I wish it distinctly understood at this time that 60 the mechanisms described in the above specification to accomplish certain movements are conventional and that such mechanisms are not to be construed as limiting the scope of the invention; minor changes and variations in the integration of several parts of each unit and in the parts 65 themselves may be resorted to without departing from the spirit of the invention; minor changes and variations in the means of transferring motion and in the synchronization of the several 70 parts of each unit and in the units themselves may be resorted to without departing from the spirit of the invention; and lastly, minor changes and variations in the means to accomplish the defined results hereinbefore developed may be 75 resorted to without departing from the scope of

the invention and without departing from the scope of the appended claims.

I claim:

1. In a lighting system for photography, a pivotal and concentric arrangement of illuminating sources movable as a unit about the fixed subject, aiming means connected therewith, means to rotate said arrangement actuated by the positioning of the said aiming means relative to the fixed subject. 10

2. In a lighting system for photography, a pivotal and concentric arrangement of illuminating sources movable as a unit about the fixed subject, aiming means connected therewith, means to rotate and vertically raise and lower said arrangement actuated by the positioning of the said aiming means relative to the fixed subject. 15

3. In a lighting system for photography, a pivotal and concentric arrangement of illuminating sources movable as a unit about the fixed subject, aiming means connected therewith, means to vertically raise and lower said arrangement actuated by the positioning of the said aiming means relative to the fixed subject. 20

4. In a lighting system for photography, a concentric arrangement of illuminating sources movable as a unit about the fixed subject, aiming means connected therewith, means to vertically raise and lower said arrangement actuated by the positioning of the said aiming means relative to the fixed subject. 25

5. In a lighting system for photography, a pivotal and concentric arrangement of illuminating sources movable as a unit about the fixed subject, aiming means connected therewith, means to rotate and vertically raise and lower said arrangement actuated by the positioning of the said aiming means relative to the fixed subject, switching means to successively illuminate different sources. 35

6. In a lighting system for photography, a pivotal and concentric arrangement of illuminating sources movable as a unit about the fixed subject, aiming means connected therewith, means to rotate and vertically raise and lower said arrangement actuated by the positioning of the said aiming means relative to the subject, switching means to successively illuminate different sources, and means to increase the brilliancy of the said sources. 40

7. In a lighting system for photography, a pivotal and concentric arrangement of illuminating sources movable as a unit about the fixed subject, the said illuminating sources being in two groups and diametrically opposed, aiming means connected with each group of illuminating sources, means to rotate and vertically raise and lower said arrangement actuated by the positioning of either of the said aiming means relative to the fixed subject. 55

8. In a lighting system for photography, a pivotal and concentric arrangement of illuminating sources movable as a unit about the fixed subject, the said illuminating sources being in two groups and diametrically opposed, aiming means connected with each group of illuminating sources, means to rotate and vertically raise and lower said arrangement actuated by the positioning of either of the said aiming means relative to the subject, switching means to successively illuminate the different sources of either group. 65

9. In a lighting system for photography, a pivotal and concentric arrangement of illuminating sources about the subject, the said illuminating sources being in two groups and diametrically 75

opposed, a mirror connected with each of said groups, means to rotate and vertically raise and lower said arrangement simultaneously with the positioning of either mirror for reflecting the full face view of the subject.

10. In a lighting system for photography, a pivotal and concentric arrangement of illuminating sources about the subject, the said illuminating sources being in two groups and diametrically opposed, a mirror connected with each of said groups, means to rotate and vertically raise and lower said arrangement simultaneously with the positioning of either mirrors for reflecting the full face view of the subject, switching means to 15 successively illuminate the sources of either group.

11. In a lighting system for photography and in conjunction with a camera shutter actuating means, a pivotal and concentric arrangement of illuminating sources about the subject, the said illuminating sources being in two groups and diametrically opposed, a mirror connected with each of said groups, means to rotate and vertically raise and lower said arrangement simultaneously with the positioning of either mirror for reflecting the full face view of the subject, switching means to 25 successively illuminate the sources of either group and to actuate the camera shutter actuating means.

12. In a lighting system for photography, a pivotal and concentric arrangement of illuminating sources movable as a unit about a fixed subject, and aiming means connected with said arrangement, said aiming means being in predetermined spatial and circumferential relationship with reference to said arrangement of illuminating sources whereby the said illuminating

sources cast light upon the subject from a predetermined angle with relation to an imaginary line drawn between the subject and said aiming means.

13. In a lighting system for photographic purposes, a pivotal and concentric arrangement of illuminating sources composed of two opposed groups, independent aiming means associated with each of said groups, each of said aiming means being in predetermined spatial and circumferential relationship with reference to the particular group associated therewith, whereby each of the groups is adapted to cast light upon the subject at a predetermined angle with reference to an imaginary line drawn from each of the aiming 15 means to the subject.

14. In a lighting system for photography, a pivotal and concentric arrangement of illuminating sources movable as a unit about a fixed subject, aiming means connected therewith comprising a mirror for the subject including a reflecting surface transparent to a light source, an image behind said surface, and a light source behind said image whereby the image may be viewed through said surface.

15. In a lighting system for photography, a source of illumination adapted for movement with relation to a fixed subject, movable aiming means associated with said source, and means to move said source in accordance with a movement of said 30 aiming means, whereby an imaginary line drawn from said aiming means to said subject will form a substantially constant angle with relation to another imaginary line drawn from said source to said subject.

SAMUEL HERSHBERG.
